UNITED STATES PATENT OFFICE.

GEORGE L. KITSON, OF PHILADELPHIA, PENNSYLVANIA.

CUT-OFF-VALVE GEAR.

SPECIFICATION forming part of Letters Patent No. 247,659, dated September 27, 1881.

Application filed February 9, 1881. (Model.)

To all whom it may concern:

Be it known that I, GEORGE L. KITSON, a citizen of the United States, residing in Philadelphia, Pennsylvania, have invented an Improvement in Cut-Off-Valve Gear, of which the following is a specification.

My invention relates to an improvement in that class of cut-off-valve gear in which the slide-valve is combined with cut-off plates arranged on the back of the valve, the movement of these plates being due to friction, and being governed by an adjustable stop or stops.

The objects of my invention are to simplify the construction of the cut-off mechanism, to prevent any undue increase in the speed of the engine owing to derangement of the governor or its connections, and to prevent too rapid a decrease in the area of the steam-passages due to the movement of the cut-off plate. These objects I attain in the manner hereinafter set forth, reference being had to the accompanying drawings, in which—

Figure 1 is a skeleton perspective view of part of the cylinder and valve-chest of a steam-engine provided with an automatic cut-off-valve constructed according to my invention; Figs. 2 to 8, diagrams illustrating the operation of the valve, and Fig. 9 a transverse section of the valve through one of the steam-ports.

30 A represents part of the cylinder, and B part of the valve-chest, of an ordinary steam-engine, D being the piston, D' the piston-rod, and E the eccentric-rod, which is connected to a gridiron-valve, F, having steam-ports *a b* and an exhaust-port, *c*, working in conjunction with the steam-ports *a' b'* and exhaust-port *c'* of the cylinder, as usual.

On the back of the valve F is a plate, G, forming the cut-off valve, said plate being held firmly against the back of the valve F by the pressure of steam, and being dependent for its movement upon this frictional contact with said valve F. A stem, *d*, projects from the plate G through a stuffing-box in the valve-chest, and this stem is provided with a yoke, *e*, which embraces a wedge-shaped block, *f*, carried by a vertical sleeve, *g*, under control of a suitable governor driven by the engine. The block *f* thus acts as a stop to limit the extent of movement of the cut-off plate G, the movement being contracted as the block is

raised, and an increased movement being permitted as the block is depressed, and the narrow portion of the wedge is brought into the path of the yoke. This variation in the movement of the plate G is caused to regulate the cutting off of steam to the cylinder of the engine, as will be understood on reference to the diagrams, Figs. 2 to 8.

Figs. 2, 3, and 4 are diagrams representing the operation of the valve when the narrowest portion of the wedge-block is in line with the stem of the plate G, the wedge occupying this position when the engine has the heaviest load. In this case the wedge exerts practically no control over the movement of the plate G, the latter moving with the valve F throughout the entire throw of the latter, so that there is no restriction of the entrance of steam into the cylinder from the beginning almost to the end of the stroke. This will be understood on reference to the diagrams, Fig. 2 showing the parts at the commencement of the stroke, with steam just entering the cylinder through the ports *a a'*, Fig. 3 showing the piston at mid-stroke and the ports *a a'* wide open, and Fig. 4 showing the piston at the end of the stroke, with the ports *a a'* closed and the opposite ports *b b'* about to open.

In Figs. 5, 6, 7, and 8 I have shown the action of the valves when the work of the engine is light and the wedge-block *f* is lifted so that the portion of greatest width is in line with the stem of the plate G, the movement of the latter being in this case very much restricted and the steam being cut off shortly after the commencement of the stroke of the piston.

Fig. 5 represents the position of the parts at the commencement of the stroke, the valve F moving in the direction of the arrow. By the time the piston has moved to the position shown in Fig. 6 the plate G has closed the steam-ports *a a'*, and these ports remain closed until the end of the stroke, the steam being worked expansively. On the reversal of the direction of movement of the valve F after the piston has reached mid-stroke, Fig. 7, the plate G moves slightly with the said valve, so as to prevent the uncovering of the port *a* of the valve before the latter has passed the port *a'* of the cylinder. (See Fig. 8.) On the return-stroke of the piston the plate G acts, in con-

junction with the steam-ports *b b'*, in the same manner. The action of the exhaust-ports *c c'* will be understood from the diagrams without explanation.

5 It will be seen that the less the movement of the plate *G* the sooner will the steam be cut off from the cylinder, and that an increase in the extent of movement of the plate lengthens the time during which steam is admitted, so that the power of the engine is directly proportioned to the work to be done, the variation in the cutting-off point being automatically effected through the medium of the governor and wedge-block. Where automatic variation 15 is not required, however, the wedge-block may be adjusted by hand, and in some cases the said wedge-block may be arranged inside the steam-chest and adapted to act directly upon lugs or projections on the back of the plate *G*, 20 a vertical stem from the block passing through the top of the steam-chest, and being attached to the governor-slide or otheradjusting device. In some cases, also, screw-stems may be passed through the cover-plate of the valve-chest, on 25 opposite sides of a lug on the plate *G*, the points of these screws inside the chest being tapered and adapted to come into contact with said lug, so that by adjusting the screws the movement of the plate *G* may be governed as desired.

30 It will be observed on reference to Fig. 9 that the ports of the valve *F* have their ends flared outward at the top, the object of this arrangement being to increase the area of the outer face of the port, so as to prevent too sudden a decrease in the area of the steam-inlet, as said outer face of the port is covered by the plate *G*.

The wedge-block *f* has at the top and adjacent to its narrowest part an expanded portion, 40 *m*, the object of which is to prevent any sudden increase in the speed of the engine in the event of the breaking of the governor-belt or other derangement of the governor which would permit the wedge-block to fall to its 45 fullest extent, for when such an accident occurs the expanded portion *m* of the block is brought into the path of the stem of the plate *G*, the movement of the latter is restricted, and the supply of steam to the engine is almost entirely 50 cut off.

When it is desired to balance the pressure

on the plate *G*, and thereby reduce the power required to move the same, the rod *E* of the valve *F* may have an arm provided with jaws for clamping the stem *d* of the plate *G*, and causing friction enough to move the plate, the jaws slipping on the stem when the movement of the plate or stem *d* is obstructed.

I am aware that it has been heretofore proposed to use in connection with the slide-valve of a steam-engine a pair of frictional cut-off plates located on the back of the valve, these plates being independent of each other, and each plate being adapted to act in conjunction with one of the steam-ports of the valve, the movement of the plates in one direction being governed by an adjustable block, and in the other direction by contact of the ends of the plates with the ends of the steam-chest casing. Such an arrangement, besides lacking the convenience and simplicity of the single plate which I employ, is also objectionable, because it necessitates the use of plates of such a size that the area of frictional contact between said plates and the valve is unduly increased and the movement of the valve impeded.

I therefore claim as my invention—
1. The combination of the cylinder of the engine and its ports, the valve *F*, the single cut-off plate *G*, and an adjustable stop or stops therefor, the movement of the plate *G* being due to friction, and said plate occupying a substantially central position on the back of the valve *F*, whereby the opposite ends of the plate are caused to govern the opposite steam-ports of the valve as the latter is reciprocated, all substantially as set forth.

2. The combination of the frictional cut-off plate *G*, the governor, and the wedge-block *f*, having an expanded portion, *m*, adjacent to the narrow portion of the wedge, as set forth.

3. The combination of the cylinder and its ports, the cut-off plate *G*, and the valve *F*, having steam-ports flared outward at the outer face, as set forth.

In testimony whereof I have signed my name to this specification in the presence of two subscribing witnesses.

GEORGE L. KITSON.
